UNITED STATES PATENT OFFICE

ROBERT H. OWENS, OF CONNERSVILLE, INDIANA, ASSIGNOR TO THE P. H. & F. M. ROOTS COMPANY, OF CONNERSVILLE, INDIANA, A CORPORATION OF INDIANA

FLUID-HANDLING APPARATUS

Application filed July 31, 1926. Serial No. 126,317.

This invention relates to fluid-handling apparatus, and particularly to a fluid meter.

One of the principal objects of this invention is to provide fluid handling apparatus which is reliable, efficient, easily assembled, and readily maintained in operating condition.

Another object of this invention is to provide rotary fluid-handling apparatus, such as a gas meter, in which the rotary members are supported in bearings which are constructed to prevent the passage thereinto of objectionable foreign matter.

Still another object of this invention is to provide fluid-handling apparatus of this character having improved mechanism for manual operation, for starting and the like.

Other objects and advantages of the present invention will be apparent from the following description when taken in connection with the accompanying drawing.

In the drawing in which like characters of reference designate like parts throughout the several views thereof,

Fig. 1 is a side elevation of a fluid meter constructed in accordance with this invention;

Fig. 2 is an end elevation of the apparatus disclosed in Fig. 1, with the cover plate for the gear housing removed, when viewed from the right-hand end of the meter;

Fig. 3 is a vertical sectional view through the gear housing and one end of the impeller casing, taken along the line 3-3 of Fig. 2;

Fig. 4 is a vertical sectional view through a portion of the manually operable crank-shaft, and mechanism associated therewith, along the line 4-4 of Fig. 3;

Fig. 5 is a vertical sectional view through the apparatus of Fig. 4, along the line 5-5; and

Fig. 6 is a vertical sectional view showing a modified form of counter drive, and shaft for manual operation.

The device shown in the drawing as illustrating a preferred embodiment of the invention is of the well-known rotary lobed impeller construction, of the widely-known "Roots' blower" type; and as disclosed is particularly adapted for the metering of gases.

This device comprises an impeller casing designated generally by the numeral 10. This casing is of generally elliptical cross section, and has an opening at the top adapted to receive a top or cover member 11, having a flanged opening 12, which is adapted for connection by means of bolts or any other suitable means with a gas supplying pipe, not shown. The casing 10 also has an opening in the bottom, which is surrounded by a flanged portion 13. This flanged portion 13 is adapted to set upon the base member bed plate 15, which has a suitable outlet passage 16 therein which connects with the lower opening in the casing, the impeller casing and base member or bed plate being connected together by means of bolts or in any other suitable manner. The passage 16 is adapted for connection to the gas delivery pipe, and preferably the gas flows through the meter in a downward direction, although this may be varied as desired. However, by having the gas flowing downwardly impurities are more readily carried through the meter and not deposited therein with possible ensuing trouble.

The impeller casing 10 is open ended, and each end is provided with a head or end plate 20, each of which is provided with two openings 21 each adapted to receive a shaft end. The openings 21 in the two end plates are arranged in alignment in pairs, to receive aligned shaft ends, each pair of shaft ends supporting a lobed impeller member, which is rotatably supported within the impeller casing. If desired the end plates may be made in sections. As shown they are made in two sections, being divided horizontally along the line 23 through substantially the center of the openings 21.

In the device illustrated the impellers are of the conventional lobed type, and their construction is therefore not shown. Each impeller may be mounted upon a shaft which extends through the waist of the impeller and through the aligned passages 21. Preferably the construction shown most clearly in Fig. 3 of the drawing is used. In this construction each impeller is provided in its opposite end with axially arranged passages 25, within

each of which is mounted a stub shaft 26, having an enlarged outer end 27, which end fits freely in the cooperating opening 21 of the end plate. The outer end of this enlarged portion of the stub shaft is provided with a bearing receiving socket or bore 28 therein, which is provided with a shoulder 29 intermediate its depth. This use of stub shafts permits of considerably reducing the weight of the impellers and this in turn cuts down the pressure differential necessary for effective operation as a meter. Supported upon a suitably formed portion 30 of the impeller casing is a standard or pillow block 31, provided with suitable grooves or passages 32 for receiving the ends of shaft members 35, there being a retaining cover or plate 36 bolted or otherwise secured, to the pillow block for firmly retaining each shaft member 35 in position. As shown the portion of the pillow block which supports the shaft members 35 is of extended width to give a firm and strong construction. The free end of each shaft member 35 extends into the socket or bore 28 of the cooperating stub shaft 26, and carries thereon the inner race of a ball bearing 40, the outer race of which is pressed into the socket 28. By means of this construction the impellers are rotatably supported upon the shaft members 35, and because of the construction shown, the mechanical resistance to free turning is very slight. As a consequence the impellers turn freely, and under a very small differential pressure, which is desirable in the metering of gases, particularly low pressure gases.

The socket 28 has positioned therein a plate 42, one face of which rests against the shoulder 29, and the other face of which rests against the outer race of the ball bearing 40. This plate 42 is also provided with a threaded opening 43. When it is desired to pull the ball bearing for any reason, the shaft members 35 having been first removed, a puller bar is threaded into the opening 43 whereupon the plate 42 may be easily withdrawn from the socket carrying the ball bearing members with it.

Mounted upon the enlarged end of each of the stub shafts 26, and fixed to the shaft to rotate therewith is a timing gear 50, of suitable construction. Preferably there are two sets of these timing gears, a pair at each end of the device, and they are so set as to mesh with each other, to insure rotation of the lobed impellers in definite timed relation with each other. If desired the timing gears may be cut to provide backlash, and the gears at one end of the casing are set to provide backlash in one direction, the gears at the other end of the casing having backlash in the other direction and being thus set against each other to compensate for this backlash. This method of setting the gears permits of securing quiet running gears without the

necessity of nice mechanical finish for the gears.

Any suitable method of mounting the timing gears upon the stub shafts 26 may be used. As shown, however, these gears are mounted upon the stub shafts, with their inner faces bearing against flanges 51, carried by the stub shafts. Each gear is provided with several bolt receiving passages 52, for receiving cap screws 53 which are threaded in cooperating threaded passages in the flanges 51 to hold the timing gears against axial movement on the shafts. The passages 52 are larger than the screws 53 so that the angular setting of the gears may be varied. And a plurality of aligned passages 54 and 55, in the gears and flanges 51 respectively, are provided to receive taper pins 56 by means of which the gears may be locked in any desired angular setting. In this way the gears may be set against each other to compensate for backlash, as set out above.

As shown the timing gears are mounted directly over the supporting bearings which greatly reduce the objectional frictional forces, strains, etc., during operation and permits of a lighter construction.

Also carried by one of the stub shafts 26 is a small gear 57. As shown this gear has an axial opening therein to receive the stub shaft and is bolted to the cooperating face of the timing gear on the same stub shaft.

A suitable cover plate 58 is clamped or bolted to the open end of each of the socket members to close the end thereof and hold the ball bearing in place. The inner face of each cover plate 58 presses against a ring 59, mounted within the socket or bore 28, the inner end of which ring presses against the outer race of the ball bearing, the cover 58 thus serving, when it is clamped in position, to force the outer race of the ball bearing against the plate 42, and thus hold the entire ball bearing assembled against longitudinal movement within the socket 28.

Each shaft member 35 is preferably provided with a flange or rib 60, which serves to impede the passage of grease outwardly from the socket 28, each shaft member 35 being also provided with a passage 61, one end of which opens into the socket 28 and the other end of which carries a suitable pressure grease connection, the arrangement being such that a heavy grease may be forced into the socket 28, during operation of the device, to maintain that socket full of grease. As a result there is a tendency for grease to leak out from around the ball bearing, rather than for impurities to leak in around the ball bearings, and the passage of objectionable impurities into the ball bearings with resultant damage to the ball bearings is thus effectively prevented. With many fluids, such for instance as ordinary city gas, the amount of objectionable impurities in the gas is very small.

However, with some gases, such for instance as coke oven gases, a considerable quantity of tar, coke breeze and the like is present in the gas, and these impurities tend to work into the bearings and wear them out very rapidly. But with the construction shown this objectionable condition will not arise, inasmuch as the grease supplied through the passage 61 tends to work through the bearing and out of the socket 28, thus preventing impurities from working into the bearings. The flange 60, the cooperating spaced in-turned flange 62, on each of the rings 59, and the cover plates 58 cooperate together to form a tortuous passage which retards the escape of grease and provides a narrow passage which is at all times filled with grease, to prevent the inward movement of impurities. Each end plate, surrounding each opening 21, is provided with a groove 65, which is in open connection with the opening 21. Each groove 65 is connected by means of a suitable passage 66 to a pressure grease connecting coupling or attachment 67, which may be of any suitable character adapted to cooperate with an ordinary grease gun or supply coupling. This construction is such that grease under pressure may be introduced into the groove 65, which grease tends to escape in both directions from the groove 65 and thus to aid in preventing the movement of impurities through the opening 21 along the shaft.

Referring particularly to Figs. 2, 4, and 5 the gear 57 is in driving connection with a gear 70, which gear is mounted upon a shaft 71, which is suitably supported in a housing member 72, which is in turn carried by a standard 73 mounted upon the pillow block 31. This supporting member 72 has a horizontally arranged passage therethrough within the opposite ends of which are mounted ball bearings 74, which rotatably support the shaft 71. This shaft 71 has mounted thereon, intermediate its length, a worm 75, which meshes with a corresponding worm gear 76, which is in turn mounted upon a vertically arranged shaft 77, which shaft is suitably supported in a vertically arranged passage in the supporting member 72. This shaft 77 is supported in free driving connection by upper and lower ball bearings 78 and 79, the upper ball bearings being held in place by means of a cover 80, which is bolted or otherwise suitably secured to the supporting member 72. This cover 80 has an upwardly extending flange 81, the upper end of which is tapered. Cooperating with the cover 80 is a packing housing 83, having a packing 84 therein, and a packing gland 85, which may be forced against the packing in any suitable manner, to provide a tight joint. The inner end of the packing member 83 is of reduced diameter, to provide a grooved shoulder 86, the groove 86 being adapted for cooperation

with the tapered flange 81 during machining operation of these parts, to insure operative alignment so that the several parts may be bored and machined together, and will properly align when thereafter assembled. Adapted for positioning within the shaft receiving passage of the cover member 80 is a collar 87, which is pinned to the shaft 77, and bears against the ball bearing 78, to hold it in position. This collar is surrounded by the grease-receiving space 88.

The flange 89 of the packing member 83 is adapted to receive bolts or any other suitable means for holding it in position.

The upper end of the shaft 77 is connected to suitable register or counter mechanism designated generally by the numeral 90, the particular construction of which is not shown, but which may be of any suitable and usual construction.

Inasmuch as the impellers must necessarily have some slight clearance with respect to the impeller housing in order to permit free movement thereof slippage of the fluid being metered past the impeller ordinarily occurs. If the differential pressure across the impellers is known, however, this slippage may be readily allowed for or the counter may be calibrated to compensate for this slippage. In order to show this slippage a suitable differential pressure gauge 95, which may be of any suitable construction, is provided, this gauge being connected differentially to opposite sides of the lobed rotary elements so as to transfer the pressure adjacent the inlet and the outlet portions of the meter to the gauge, which indicates the slippage so that the readings of the counter may be corrected to compensate for this slippage.

As shown one end of the shaft 71 has the gear 70 mounted thereon. The other end is provided with a slot 100, for receiving a suitable crank, whereby the shaft 71 may be manipulated as desired. It sometimes happens that where gases of very low pressure are being metered, the differential pressure across the impellers is not sufficient to overcome the inertia of the parts and start the meter. Under such circumstances the crank may be applied to the outer end of the shaft 71 so that the meter may be turned over by hand. Furthermore in assembling, the crank may be used to turn the impellers so as to position the timing gears thereon to insure assembling with the impellers in proper time.

Each end plate 20 is provided with an outwardly extending flange 105, which extends sufficiently to completely overlie the gear mechanism thus far described. Each flange is also provided with a cover plate 106, which is arranged to be clamped, gas tight, against the free end of the flange. Consequently the gears are maintained in a chamber or housing which is sealed against leakage to the

outside. But it is necessary that access may be had to the shaft 71 from outside this housing. As shown, particularly in Fig. 5, one of the cover plates 106 is provided with an opening 107 which receives one end of the supporting member 72. It also receives a flanged sleeve 108, which is adapted to enclose the outer end of the shaft 71 and to be bolted or otherwise suitably secured to the cover plate 106. The inner end 109 of this sleeve 108 is extended so that when assembled it extends partly into and partly receives the outer end of the supporting member 72 as indicated in Fig. 5. This inner extended end is also provided with a shoulder 110, adapted to cooperate with the free end of the supporting member to compress a packing 111 therebetween, to prevent leakage between the outer face of the sleeve 108 and the outer end of the supporting member 72. The passage within the sleeve 108 is enlarged, at the inner end to receive a compression sleeve 115, the inner end of which rests against the outer ball bearing for the shaft 71 and the outer end of which rests against a packing 116, which surrounds the shaft 71 and is pressed against a shoulder 117, within the passage within the sleeve 108 along the shaft 71. The sleeve 108 is provided with a cap 120 which is preferably threadedly mounted on the outer end of the sleeve 108 to completely close off the outer end of the passage through the sleeve and to cover the outer end of the shaft 71, when the starting crank is not in use.

The sleeve 108 is provided with a lubricant passage 125, having a lubricant attachment 126, by means of which grease may be introduced under pressure into the enlarged inner end of the passage in the sleeve 108, and thence into the interior of the supporting member 72. This grease is introduced under pressure and therefore tends to work out of the supporting member, through the inner ball bearing, and so into the interior of the gear housing chamber. As a consequence the passage of objectionable impurities into the interior of the supporting member is prevented.

Lubricating oil is maintained, during operation, within the gear chamber to immerse the lower portions of the timing gears and thus provide lubrication.

In Fig. 6 is shown a slightly modified form of actuating mechanism for the counter in which beveled gears 150 and 151 are used in place of the worm and helical gears as shown in the modification illustrated in Figs. 4 and 5. In this construction the supporting member 72' is provided with a cap 80', which has a considerably elongated extension 81' for supporting the shaft 77'. Suitable ball bearings 78' and 79' are provided at the upper and lower ends respectively of this cover extension, suitable packing preferably being

positioned above the upper ball bearing to make a tight joint. The sleeve 108' is provided with a passage 125', having a lubricant attachment 126' similar to the attachment 67 at the outer end, the function of which is exactly the same as the corresponding passage described above in connection with Figs. 4 and 5.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A fluid handling apparatus comprising a casing having a fluid passage therein, a rotor disposed in said passage and adapted to cooperate with the fluid therein, a supporting means, and a shaft extending from said supporting means for rotatably supporting said rotor, and means on said rotor surrounding said shaft in bearing relationship therewith.

2. A fluid handling apparatus comprising a casing having a fluid passage therein, a rotor disposed in said passage and adapted to cooperate with the fluid therein, a supporting means, and a shaft extending from said supporting means for rotatably supporting said rotor, and means on the rotor having a socketed bearing connection with the shaft.

3. A fluid handling apparatus comprising a casing having a fluid passage therein, a rotor disposed in said passage and adapted to cooperate with the fluid therein, means for rotatably supporting said rotor, said means comprising an inwardly extending shaft projecting toward the said fluid passage, and means on said rotor providing a lubricant containing chamber adapted to receive said shaft in bearing relationship therewith, said shaft having means associated therewith for supplying lubricant to said chamber.

4. In a fluid meter, a casing having a fluid passage therein, a rotor disposed in said passage and adapted to be actuated by the fluid passing therethrough, an end plate for said casing, and means for rotatably supporting said rotor on the exterior of said end plate, said means comprising a shaft member and cup means on said rotor surrounding said shaft in bearing relationship therewith.

5. In a fluid meter, a casing having a fluid passage therein, a rotor disposed in said passage and adapted to be actuated by the fluid passing therethrough, an end plate for said casing, and means for rotatably supporting said rotor on the exterior of said end plate, said means comprising a shaft member, an outwardly facing cup member carried by said rotor and surrounding the end of said shaft member, and anti-friction means interposed

between said cup member and said shaft member.

6. In a fluid meter, a casing having a fluid passage therein, a rotor disposed in said passage and adapted to be actuated by the fluid passing therethrough, an end plate for said casing, and means for rotatably supporting said rotor exteriorly of said end plate, said means comprising a shaft extending towards said rotor, an outwardly facing cup member carried by said rotor and surrounding the inwardly extending end of said shaft, anti-friction means interposed between said cup member and said shaft, said shaft having means associated therewith for supplying lubricant to said cup member and anti-friction means.

7. A fluid handling apparatus comprising a casing having a fluid passage therein, a 20 pair of lobed rotary elements mounted within said passage and adapted to cooperate with the fluid passing therethrough, shafts for said rotary elements extending through the end walls of said casing, and means for rotatably supporting said rotary element shafts on the exterior of said casing, said means comprising a short shaft member positioned at each end of each of said rotary element shafts and in alignment therewith respectively, and means on each said rotary element shaft surrounding its cooperating short shaft member in bearing relationship therewith.

8. In a fluid meter, a casing having a fluid passage therein, a pair of lobed rotary elements mounted within said passage and adapted to be actuated by the fluid passing therethrough, shafts for said rotary elements extending through the end walls of said casing, and means for rotatably supporting said 35 rotary element shafts on the exterior of said casing, said means comprising short shafts positioned one at each end of each of said rotary element shafts and in alignment therewith respectively, said rotary element shafts having outwardly facing cups at the ends thereof surrounding the ends of said short shafts, and anti-friction means interposed between each rotary element shaft and its cooperating short shaft.

- 50 9. A fluid handling apparatus comprising a main casing having a fluid passage therein, a rotor within said passage adapted to cooperate with the fluid therein, said rotor having a part thereof extending through the end wall of said casing, and means forming an externally gas-tight compartment enclosing the extended end of said rotor, and means in said compartment for rotatably supporting said rotor, said last mentioned means comprising an inwardly extending shaft projecting toward the said rotor, said part surrounding the projecting end of said shaft in bearing relationship therewith.

- 60 10. A fluid handling apparatus comprising a main casing having a fluid passage therein,

a rotor within said passage adapted to cooperate with the fluid therein, said rotor having a part thereof extending through the end wall of said casing, means forming an externally gas-tight compartment enclosing the extended end of said rotor, means in said compartment for rotatably supporting said rotor, said last-mentioned means comprising a shaft, said part providing a lubricant-containing chamber adapted to receive said shaft in bearing supporting relationship therein, said shaft having means for supplying lubricant to said chamber.

70 11. A fluid handling apparatus comprising a casing having a fluid passage therein, a 80 rotor within said passage and adapted to cooperate with the fluid therein, a rotor shaft extending to the exterior of said casing, said rotor shaft and casing having a lubricant receiving groove therebetween for substantially preventing fluid leakage from the casing past said rotor shaft, and having means for supplying lubricant to said groove.

85 12. A fluid handling apparatus comprising a main casing having a fluid passage therein, a rotor within said passage and adapted to cooperate with the fluid therein, said rotor having a supporting shaft extending to the exterior of said casing, a substantially fluid-tight compartment surrounding said rotor shaft, bearing means within said compartment for said rotor shaft, and means for substantially preventing leakage between the interior of said casing and said compartment, said means comprising a lubricant groove formed in said casing and surrounding said rotor shaft, a lubricant passage communicating with said groove and leading to a readily accessible point on the exterior of said casing, and means associated with said passage for receiving pressure lubricant supplying means.

90 13. A fluid handling apparatus comprising a casing having a fluid passage therein, a pair of lobed rotary elements mounted therein and having supporting means projecting through the end walls of said casing, and means for rotatably supporting said supporting means comprising a pillow block at each end of said casing, each pillow block supporting said supporting means of both of said rotary elements, said pillow blocks being detachably connected with the exterior of said casing.

110 14. A fluid handling apparatus comprising a main casing having a fluid passage therein, a pair of lobed rotary elements mounted therein and having their shafts projecting through the end walls of said casing, means for rotatably supporting said shafts comprising a pillow block at each end of said casing adapted to support the shafts of both of said rotary elements, said pillow block being detachably connected with the exterior of said main casing, and means providing a 115 120 125 130 135 140

gas-tight compartment enclosing said pillow block and the cooperating shafts of said rotary elements.

15. A fluid meter comprising a casing having a fluid passage therein, a pair of lobed rotary elements mounted therein and adapted to be actuated by the fluid passing therethrough, shafts for said rotary elements extending through the end walls of said casing, and means for rotatably supporting said rotary element shafts at the exterior of each end of said casing, said means comprising a standard detachably connected with the exterior of said casing, a pair of shaft members carried by said standard in alignment with said rotary element shafts respectively, and means on said rotary element shafts surrounding the ends of said shaft members in bearing relationship therewith.

20. 16. A fluid meter comprising a casing having a fluid passage therethrough, a rotor in said passage adapted to be actuated by the fluid passing therethrough, a counter mechanism adapted to be driven from said rotor, a driving connection between said rotor and said counter mechanism, said driving connection including a drive shaft operatively connected with said rotor, a counter shaft connected with said counter mechanism, operating gears on said drive shaft and said counter shaft respectively, said drive shaft having provision whereby it may be manually actuated to thereby actuate said rotor.

25. 17. A fluid meter comprising a casing having a fluid passage therethrough, a rotor in said passage adapted to be actuated by the fluid passing therethrough, said rotor having an extension extending through the end of said casing, a substantially fluid-tight compartment surrounding the extended end 30 of said rotor, counter mechanism, a driving connection between said rotor and said counter mechanism, said driving connection including a drive shaft connected with said 35 rotor within said compartment, said drive shaft extending through the wall of said compartment to the exterior thereof for manual operation, said compartment having means for supplying lubricant to said 40 drive shaft to prevent fluid leakage to the exterior of said compartment past said drive shaft.

45. 18. A fluid handling apparatus comprising a casing having a fluid passage therein, a 50 rotor disposed in said passage and adapted to cooperate with the fluid therein, said rotor having a supporting member extending through the end wall of said casing, means for rotatably supporting the extended member of said rotor, said means comprising a short shaft, cup means carried by the extended 55 member of said rotor and surrounding said short shaft in bearing relationship therewith, and a gear carried by the extended

member of said rotor and surrounding said bearing support.

19. A fluid handling apparatus comprising 70 a casing having a fluid passage therein, a pair of lobed rotary elements mounted therein and adapted to be actuated by the fluid passing therethrough, shafts for said rotary elements extending through the end walls of said casing, bearing means for rotatably supporting said rotary element shafts on the exterior of said casing, and intermeshing gears carried by said shafts, each of said gears surrounding the bearing means of its respective shaft.

20. A fluid handling apparatus of the 80 class described comprising a casing having a passage therethrough, a rotor in said passage adapted to cooperate with the fluid therein, said rotor having an extension extending through the end of said casing, a substantially fluid-tight compartment surrounding the end of said rotor extension, a starting drive shaft in said compartment and extending to the exterior thereof through an outer wall of said compartment, a driving connection for said starting drive shaft continuously in driving engagement with said rotor, packing means in the outer wall of said compartment for said starting drive shaft, and a cover plate covering the outer 85 end of said starting shaft to normally prevent all leakage through said packing.

21. A fluid handling apparatus of the 90 class described comprising a casing having a fluid passage therein, a rotor within said 95 passage adapted to cooperate with the fluid therein, said rotor having a supporting shaft extending to the exterior of said casing, a substantially fluid-tight compartment surrounding the extended end of said rotor shaft, supporting means in said compartment in bearing engagement with said rotor shaft, said casing having a lubricant groove surrounding the rotor shaft substantially preventing leakage between the interior of 100 said casing and said compartment having a passage for supplying lubricant to said groove, and a gear fixed to said rotor shaft and provided in said compartment between 105 said supporting means and said lubricant groove.

In testimony whereof I hereto affix my signature.

ROBERT H. OWENS.
